UNITED STATES PATENT OFFICE.

WILLIAM N. OEHM, OF MICHIGAN CITY, INDIANA.

CAR-BODY.

1,329,006.

Specification of Letters Patent.

Patented Jan. 27, 1920.

Application filed February 21, 1919. Serial No. 278,435.

To all whom it may concern:

Be it known that I, WILLIAM N. OEHM, a citizen of United States, and resident of Michigan City, county of Laporte, and State of Indiana, have invented certain new and useful Improvements in Car-Bodies, of which the following is a specification, and which are illustrated in the accompanying drawings, forming a part thereof.

10 The invention relates to improvements in car bodies. The object of the invention is the placing of the metal in the structure of a car body to the best advantage for the resistance to stresses and for increased life 15 under corrosion. A further object of the invention is the provision of a car body having stiffening means which shall give more than the usual stiffness to a car body in proportion to the amount of metal utilized.

20 In the accompanying drawings:

Figure 1 is a side view of one end of a car body, the invention being illustrated as applied to a gondola car body;

Fig. 2 is a vertical transverse section 25 taken on the line 2—2 of Fig. 1, the side sill being shown in a different position from that of Fig. 1;

Fig. 3 is a view similar to Fig. 2 of the bottom portion of a stake and web plate, 30 showing a different arrangement of metal.

Fig. 4 is a side view of one corner of a car body, showing a different structure of corner from that illustrated in Fig. 1,

Fig. 5 is a vertical section taken on the 35 line 5—5 of Fig. 4,

Fig. 6 is a transverse section taken on the line 6—6 of Fig. 4, and

Figs. 7 and 8 are vertical sections on an 40 enlarged scale taken on lines 7—7 and 8—8 respectively of Fig. 6 the web plate being omitted.

A side web plate is shown, indicated at 1, and it will be observed in Fig. 2, that this plate is thickest at the bottom edge and 45 tapers gradually to its thinnest portion at the upper edge. Riveted to this web plate is shown a stake or stiffening rib 2, which stake is made up of two flanges 3 and a central raised rib 4. As shown, in Fig. 2, 50 the metal of this stake is thickest at its bottom 5, both in its rib portion and in its flanges, and tapers as does the metal of the web plate.

In Figs. 3 to 8 inclusive a different ar-

range ment of metal from that shown in Fig. 2, and one coming within the purview of my invention, is shown. In this form of the invention the greatest thickness of metal in the web plate and in the flange and rib of the stake is shown at the point 20 substantially at the level of the car floor 21. This is the actual point of the greatest bending stress as well as the greatest probable corrosion of the web plate. From this point the metal of both stake and web plate tapers both upwardly and downwardly.

The corner plate shown at 6, the stakes 2 and the end braces 8 and braces 9, shown in these figures, may be used with web plates of other material, as wood, or web plates may be omitted altogether and the parts named may be utilized as a skeleton body.

In the modification of Fig. 5 the corner plate 6 as well as web plate 1 has its greatest thickness at the point 10 on a level with the car floor, tapering from this point both upwardly and downwardly.

The end braces 8 are shown as made up of side flanges 11 and end flanges 12. The central portion of the brace is struck up into a rib, as shown at 13, which rib, as shown, terminates short of the ends of the brace though it may be coextensive with the brace, and is preferably higher at its center than at its ends. The brace is shown bent at an angle to the length of the brace so as to lap past the ends of the car. As indicated in Figs. 6 to 8, the metal of the brace, both of its flanges and its rib is thicker at the center than toward the ends, thus producing additional strength of the rib where the greatest bending stresses occur. The features of construction of the car body shown on the drawings, without reference characters, merely indicate the usual construction of a car and form no part of the present invention.

The arrangement of metal according to my invention will produce a car body of the usual weight but much stiffer than the old arrangement and will, moreover, produce a car body which will have a longer life under corrosion due to the fact that there is more metal to be corroded away at the points where greatest corrosion occurs than is the case with the usual arrangement. Moreover, with a car body of the usual

weight, due to its additional effective strength and stiffness, a lighter underframe may be used.

I claim as my invention—

5. 1. A car stiffening member comprising a central rib portion and flanges, the height of the rib and the thickness of material of both the rib and the flanges being greater in the region of greatest expected bending 35 stresses.
10. 2. A car body comprising web plates, and stakes the metal of which each of said members is composed being thickest near its lower portion and decreasing in thickness toward its upper portion.
15. 3. A car body comprising web plates, and stakes each of said members being thickest in the portion at the approximate level of the floor of the car and of decreasing thickness both above and below this plane.
20. 4. A car body comprising, in combination, a corner member having its greatest thickness at its lower portion and which diminishes in thickness toward its upper portion, and an end brace attached to said corner member comprising flanges and a longitudinal raised central portion, the material of the flanges and of the raised portion being thickest opposite the center of the end of the 25 car.
25. 5. A car body comprising, in combination, a corner member whose thickness both up- 30ward and downward tapers from a maximum at the approximate level of the floor of the car, and end braces attached to said 35 corner member comprising a flange portion lapped about the corner member and a longitudinal raised portion, the projection of the raised portion above the flanges and the thickness of material of both raised portion 40 and flanges being greatest at the center of the car end.
30. 6. A car body comprising structural members, the metal of said members being thicker at those portions where greatest 45 stress is to be resisted, and tapering uniformly to portions where less stress is to be resisted.
35. 7. A car body comprising a web plate, the metal of said plate being thickest at its 50 lower portion and tapering uniformly to its upper portion.
40. 8. A car body comprising a corner member the material of which the member is composed having its greatest thickness at its 55 lower portion and which diminishes in thickness toward its upper portion.
45. 9. A car body comprising an end brace having flanges and a longitudinal raised portion, the material of which the raised 60 portion and the flanges are composed being thickest at the central portion of the brace.

WILLIAM N. OEHM.
